UNITED STATES PATENT OFFICE

2,439,932

CHANGEABLE EXHIBITOR HAVING A SERIES
OF ROLLERS WITH WEBS

Job Hutchinson, Great Neck, N. Y.

Application February 10, 1944, Serial No. 521,832

10 Claims. (Cl. 40—84)

1

This invention relates to a display apparatus or machine whereby a plurality of displays, such as curtains or sign sheets, posters and the like, containing advertising or other intelligence matter, are severally and successively displayed and each for a predetermined period of time.

More particularly, the invention relates to a display apparatus or machine of the character disclosed in United States Patents No. 2,190,426 of February 13, 1940, No. 2,195,249 of March 26, 1940, and No. 2,410,975 of November 12, 1946, granted to me.

The principal object of the invention is the provision of an apparatus or machine of the indicated character which embodies improvements whereby advantages are attained, among which are the following. It facilitates installation, replacement and repair of parts. Electrical mechanism for controlling the lighting and for operating the sign units are conveniently accessible and are so assembled and arranged as to meet underwriter's requirements. The sign units or displays are transferred noiselessly. The sign curtains, sheets or posters are displayed without liability of being torn or mutilated and are kept flat and even when displayed. The driving mechanism is conveniently housed so that oil and dirt are prevented from reaching the sign curtains, sheets or posters.

With the foregoing, other objects of the invention will appear when the following specification is read in conjunction with the accompanying drawings, in which

Fig. 1 is a vertical sectional view of an apparatus embodying the features of the invention, the section being taken approximately on the line 1—1 of Fig. 2.

Fig. 2 is a vertical sectional view taken approximately on the line 2—2 of Fig. 1.

Fig. 3 is a side view showing a panel removed to afford access to the driving chain.

Fig. 4 is an enlarged fragmentary sectional view illustrating the manner in which the sign units are brought to the display position.

Fig. 5 is a perspective view of one end of a sign unit.

Fig. 6 is a view of one of the sign units, the spring roller assembly being shown in longitudinal section.

Fig. 7 is a fragmentary view of one end of a sign member or poster.

Fig. 8 is an enlarged fragmentary perspective view showing certain features of the end construction of a sign member or poster.

2

Fig. 9 is an enlarged fragmentary sectional view showing the sign unit back check means.

Fig. 10 is a sectional view taken on the line 10—10 of Fig. 9.

Fig. 11 is a top plan view partly in section showing certain features of the driving mechanism.

Fig. 12 is an enlarged sectional view of the clutch of the driving mechanism.

10 Fig. 13 is a side view looking at the clutch in the direction indicated by the arrow 13 of Fig. 12.

Referring now to Figs. 1, 2 and 3, it will be apparent the apparatus or machine includes a substantially rectangular casing, housing or cabinet 10 consisting of side walls 11, top wall 12, bottom wall 14, back wall 15 and front wall 16 having a sight or window opening 17.

Each of the side walls 11 has a removable panel 18. The side, top, bottom and back walls are connected to each other by any suitable means.

20 The front wall 16 is removably held in place by small slotted brackets 19 on the wall 16 which engage pins 20 on the side walls 11, as shown in Fig. 2. A horizontal partition or separator 21 is interposed between the side walls and spaced a short distance above the bottom wall to provide a compartment for parts of the driving mechanism and electrical equipment to prevent oil and dirt from reaching other parts of the apparatus.

25 The back wall has openings therein at the top and bottom and the partition 21 also has openings therein. The openings are designated 22. Strips 23 are attached to the back wall 15 on the outside thereof for the purpose of keeping the apparatus spaced from any flat surface. It will be apparent air may pass from a point at the bottom of the cabinet upwardly through and out of the same at the top, thereby giving a complete air circulation throughout the interior of the apparatus.

30 Each of the side walls 11 has a continuous groove or track formed therein at the inside thereof to provide a closed loop guideway 30. Each guideway consists of two vertical straight runs 31 and 32, respectively, joined by a lower semi-circular run 33 and an upper run 34 consisting of turns or bends 35 merging into the upper ends respectively of the runs 31 and an intermediate straight portion 36 in continuation of the turns 35. The side walls 11 may be made of wood or other suitable material and the guideways 30 are formed directly therein instead of using an additional frame structure to simplify the construction.

35 40 45 50 55

The guideways 30 serve for guiding a plurality of similar sign units 40 along a prescribed path for the intended purposes. It is to be understood that any suitable number of units 40 may be used. In Figs. 1 and 4 of the drawings only a sufficient number of the units 40 are shown to make the operation clear and so as to expose other parts of the machine. The units 40 are identical in construction and operation. Therefore, a description of one will suffice for all. A unit 40 consists of a carrier 41 and a spring roller 42 on which is wound or unrolled a sign member, poster, curtain or sheet 43. These may be made of any suitable translucent material, such as stout paper, cloth, or other flexible sheet material on which is imprinted advertising or other intelligence matter of various kinds. The carrier 41 consists of a shaft 44 and runners in the form of shoes or slides 45 on the opposite ends respectively of the shaft 44. The roller 42 is of the shade roller type but without a ratchet and its spring 49 serves for rewinding or rerolling the sign member thereon, the spring being put under tension when the sign member is unwound. The roller 42 is operatively mounted on the shaft 44 between two collars 47. Each collar 47 is held in place on the shaft by a set screw 48. Each runner 45 is developed from a single strip of spring steel to form an 8 shape structure providing open substantially circular portions 49 joined by an intermediate straight portion 50. The portion 50 is received in a kerf in the end of the shaft. Pins 51 or the like extend through the shaft end and the portion 50 to hold the runner in place. The roller 42 is first arranged on the shaft 44 after which the collars 47 are put in place. The collars prevent the axial movement of the roller 42. The opposite ends of the shaft 44 project beyond the collars 47 respectively. Tubular bumpers 52 are arranged on the projecting end portions respectively of the shaft and these bumpers 52 are held in place by the collars 47 and the runners 45. The runners, of course, are secured to the shaft after the bumpers 52 are put in place. These bumpers are made of suitable resilient material, such as for instance as suitable lengths of rubber tubing. The novel type of runners and the bumpers eliminate metallic clicking sounds in the pick-up and delivery of each sign unit 40. The portions 49 of the runners being of open loop construction enable the portions to expand or contract and so are especially adapted to travel in the guideways 30 without any binding action and almost noiselessly.

It is to be understood a sufficient number of the sign units are used to enable the display of the sign members 43 successively one at a time at the sight opening 17. Therefore, the units 40 will follow each other, the runners 45 of one unit, contacting the runners of the one ahead of it, with respect to the direction of travel of the units. They travel downwardly at the back of the cabinet, then forwardly, then upwardly and then backwardly completing a cycle. Travel of the units 40 is in part by gravity and partly by positive application of mechanical force.

In order to cause the display of the sign member 43 of each unit 40 by unrolling the member, prior to the upward travel of the unit, the member or sheet 43 has a pull-rod 53 extending through a tunnel 54 on the outer end thereof. The opposite ends of the pull-rod 53 project beyond the ends respectively of the tunnel and said ends of the pull-rod each has a hole 55 therein. The holes 55 receive therein the set screws 48

respectively of the carrier 41 of the next preceding sign unit. It is therefore understood as one sign member 43 of one unit is being unrolled for display prior to the upward travel of the unit, a preceding sign member 43 of a second unit is being rerolled as the second unit travels upwardly as shown in Fig. 4.

Pick-up means is provided for moving the units 40 upwardly one at a time. Said means includes a shaft 60 supported for rotation by adjustable brackets 61 on the side walls 11, respectively, near the top of the cabinet. Another shaft 62 is supported for rotation by suitable bearings 63 on the walls 11. Sprockets 64 are fast to the shafts 60 and 62 and they are arranged in pairs, there being one pair at each side of the sight opening 17 in proximity to the side walls 11. A chain 65 encircles the sprockets 64 of each pair. Each chain 65 has a special link which is provided with a lug 66 having an anti-friction roller 67. In each cycle of the chains the rollers 67 engage the bumpers 52 respectively of a sign unit 40 indicated in Fig. 4, the particular unit being identified by the letter A. The unit is carried upwardly by the rollers 67 on the lugs 66, and is shown in dotted lines on the way up, allowing its sign member to be rerolled while unrolling the sign member 43 of the next succeeding unit 40 identified by the letter B. Thus, each sign member 43 is fully displayed at the sight opening 17.

When each sign unit 40 reaches its up position, it is dogged or held from moving back or down after the pick-up means clears the bumpers 52 of the unit. A back-check means at each side of the opening 17 is provided for this purpose. Said back-check means consists of a dog or check member 70 pivotally mounted on a stud 71 on the adjacent side wall 11. A contractile spring 72 has one end connected with the tail 73 of the dog 70 by a stud 74 and the opposite end of the spring is connected with a securing element 75 on the wall 11. The springs 72 yieldingly retain the dogs 70 in the checking position so that as each unit 40 moves upwardly the bumpers 52 encounter the dogs 70 respectively and move them on their pivots to allow the unit 40 to clear after which the springs 72 quickly return the dogs to the checking position in engagement with said bumpers to keep the particular unit 40 and those immediately ahead of it from moving back down, as indicated in Fig. 9.

There is provided holding and releasing means which cooperates with the back-check means to eliminate the use of a special timing gear and to make the movement of the units 40 more reliable and simplified. Said holding and releasing means consists of stop levers 80 fulcrumed as at 81 on the side walls 11, respectively. The upper ends of the levers 80 are pivotally connected, as at 82, with short links 83, respectively, and said links in turn are pivotally connected with the studs 74 respectively. As the dogs 70 move out of the checking position, the levers 80 are operated to release a unit 40 to be subsequently engaged by the pick-up means. Normally the lower ends of the levers engage the bumpers 52 of each unit 40 as it is brought into position for the unrolling of its sign member 43. This unit designated B is in this unrolling position. The levers 80 thus hold the unit against upward movement during the pull on its sign member 43 to unroll the same in response to the upward movement of the unit designated A. This unit A operates the back-check means which in turn operates the levers 78 80 to release the unit B to the pick-up means.

In order to hold the sign member 43 of each unit 40 taut while it is displayed, there are provided bars 84 which are pivoted on the fulcrums 81 respectively. The upper end of each bar is connected with one end of a contractile spring 85 whose opposite end is connected with a securing element 86 on the adjacent side wall 11. The lower ends of the bars 84 are rounded to provide cams 87 which cooperate with the bumpers 52, to not only hold each sign unit presented thereto while it is stationary, but also to move said bars 84 to a releasing position as the unit is moved upwardly by the pick-up means. The springs 85 return the bars 84 to their functioning position. The lower ends of the bars 84 terminate above the lower ends of the levers 80 a distance to insure the temporary retention of each unit 40 in a position for the pick-up operation by the lugs 66. As each unit 40 reaches its up position it causes a release of a unit in the advance ends of the runs 33, by reason of the operation of the parts 70, 83 and 80. There is a lever 80 and a bar 84 in proximity to each other at each side of the cabinet. A resilient stop 8 serves as a bumper for the associated lever and bar to noiselessly limit the movement thereof to the functioning position.

In order to retain the sign member 43 of each unit smooth and in parallelism with the front wall there are provided spaced parallel slats 90, 30 each pivotally connected as at 91 with radius arms 92 pivotally connected as at 93 with brackets 94, respectively, on the adjacent side wall 11, as shown in Fig. 1. A dash-pot 95 is connected with the arms 92 between the same. The dash-pot consists of a rod 96 having one end pivotally connected with one arm 92 and the other end of the rod has a plunger 97 which operates in a cylinder 98 pivotally connected with the other arm 92. A check valve 99 controls the flow of air into and out of the cylinder 98. The lower ends of the slats 90 are rounded so that the bumpers 52 will cause the slats to move rearwardly and upwards as the sign unit moves upwardly. The slats return by gravity action after the unit reaches its up position to gently press against the unrolled sign member being displayed. The dash-pots control the movement of the slats, and prevent any sudden or jerky motion of the slats and connected parts. Stop pins 88 on the walls 11, respectively, prevent the slats from moving too far on the return, engaging the lower arms 92.

It is to be noted the sign units 40 move downwardly by gravity at the back of the cabinet and push one unit at a time into position to be picked up every time a unit is delivered to the back-check means. In order to prevent a sudden or quick movement there are provided latches 100 which cooperate with the bumpers 52, respectively, of each unit 40. Each latch 100 has a cam 101 on its lower end while the upper end has connected therewith one end of a contractile spring 102 whose opposite end is connected with a securing element 103 on the adjacent side wall 11. The latches 100 sustain a portion of the weight of the units 40 above the same in the runs 32 of the guideways. The delivery of a unit 40 into the upper runs 34 pushes the whole series of units 40 so that there is always one in position ready to be picked up.

The driving power is derived by the use of an electric motor 110 mounted on a base 111 having rubber cushions 112 resting on the bottom wall 14 near the right side of the cabinet. A gear box 113 is also mounted on the base 111 and this box

contains reduction gearing, generally designated 114, and including a power input shaft 115 and a power output shaft 116. See Fig. 11. A clutch 117 is connected with the shaft 115. The clutch consists of a pulley 118 loose on the shaft 115 and a disk 119 fast on said shaft. The pulley 118 is held against axial movement by collars 120 fast on the shaft 115 as shown in Fig. 12. The pulley 118 carries pivoted brake members 121 each having a roller 122. The members 121 are under the influence of tension springs 123 connected with lateral rods 124 on said members 121 as shown most clearly in Fig. 13. The brake members 121 cooperate with the disk 119 which has depressions 125 in the periphery thereof. Under normal action the rollers 122 are disposed in the depressions 125 respectively and effect the required normal power torque. A belt 126 encircles the pulley 118 and a pulley 127 on the motor shaft 128. Any overload or stall for any reason will cause the clutch to slip since the rollers 120 will ride out of the depressions and move around on the disk 119. This will prevent damage to the parts and also prevent the motor from burning out. A driving chain 129 encircles a sprocket 130 fast to the shaft 116 and a sprocket 131 fast to the shaft 62. Thus rotary motion is transmitted from the motor 110 to the shaft 62 through the intervention of the parts 114-131. The sprockets 130 and 131, as well as the chain 129, are disposed between the panel 18 and the right hand side wall 11. This panel 18 may be removed to afford access to the said chain 129 and the sprockets 130 and 131. A bolt and nuts 132 connect the box 113 with the base 111 for adjustment to keep the chain 129 under proper tension.

Spaced vertical plates 133 carried by supports 134 extending from the side walls 11 have arranged thereon certain electrical appurtenances including lighting elements such as the fluorescent tubes 135 backed by a reflector for lighting the sign members 43. Also a junction-box 136 is arranged on the left-hand side wall 11. This box 136 supports two terminals from the lighting circuit, two terminals from the motor circuit, two terminals for the line and two terminals for a fuse, all properly electrically connected with two control switches for the lighting and motor circuits. Access to these parts is afforded by the removal of the left-hand panel 18. An extension cord 137 for supplying a suitable source of voltage is provided. This cord may be drawn into the cabinet below the partition 21 and thus be protected during shipment of a machine. The cord may be withdrawn readily when the machine is to be put into operation. All electrical appurtenances are installed to pass the requirements of underwriters.

It is to be understood that changes in the details of construction and arrangement of the parts may be resorted to without departing from the spirit of the invention as expressed in the appended claims.

I claim:

1. In a sign display apparatus of the type having sign units which travel periodically along a continuous guideway, each unit having a sign member which may be unrolled while the unit is stationary and rerolled during travel and the sign member of each unit having one end attached to a second unit in advance of it, the combination of pick-up means to move the units successively one at a time, holding and releasing means to engage each unit as it is presented thereto to hold it while a second unit is being advanced by said pick-up

means to unroll the sign member of the held unit and to enable the sign member of the advancing unit to be rerolled, and back-check means connected with the holding and releasing means actuated by the movement of the advancing unit causing the operation of the holding and releasing means to release the held unit so that it may be advanced in due order.

2. In a sign display apparatus as set forth in claim 1, wherein said holding and releasing means includes spring actuated holding and releasing members.

3. In a sign display apparatus as set forth in claim 1, wherein said back-check means consists of spring actuated pivoted members normally extending in the path of movement of said sign units.

4. In a sign display apparatus as set forth in claim 1, wherein said holding and releasing means consists of holding and releasing members, and said back-check means consists of spring actuated pivoted members linked to said holding and releasing members respectively, said pivoted members normally extending in the path of movement of said sign units.

5. In a sign display apparatus as set forth in claim 1, wherein said back-check means consists of spring actuated dogs connected with said holding and releasing means which not only actuate the holding and releasing means but also prevent the return movement of each sign unit.

6. In a sign display apparatus of the type having sign units which travel periodically along a continuous guideway, each unit having a sign member which may be unrolled while the unit is stationary and rerolled during travel and the sign member of each unit having one end attached to a second unit in advance of it, the combination of pick-up means to move the units successively one at a time, a pair of members, means connected with said members operated by the movement of each sign unit to hold each unit presented to said pairs of members so that its sign member may be unrolled and to release said unit at a predetermined time after its sign member has been unrolled, and a second separate pair of spring actuated members operable to engage and temporarily hold the unit whose sign member is unrolled from advancing.

7. In a sign display apparatus of the class in which sign units of the curtain roller type travel around a closed circuit and wherein one unit while

in an up position cooperates with another unit in a down position to retain sign curtain of the unit in the down position displayed; the combination of dogging means to prevent backward movement

5 of the unit in the up position, and means to hold the unit in the down position from moving upwardly while its sign curtain is being displayed; said dogging means connected with and causing the operation of said last means to release the 10 unit in the down position so that it may be moved upwardly.

8. A sign unit of the curtain roller type including a carrier for the roller, said carrier having runners on the opposite ends respectively, each of 15 said runners consisting of a strip of material bent and formed to provide open loop resilient portions adapted for sliding movement to afford traction means for the unit, and in combination, guideways traversed by said loop portions.

9. A sign unit of the curtain roller type including a carrier for the roller, said carrier having runners on the opposite ends respectively adapted to traverse closed loop guideways, each of said runners consisting of a strip of material providing a straight attaching portion intermediate open loop resilient portions adapted to slide along said guideways.

10. In a sign display apparatus of the class having traveling sign units of the curtain roller type 30 and wherein each of said units has a sign curtain which is displayed while unrolled, means to retain said curtain evenly spread flatwise while unrolled, said means consisting of spaced slats, pivoted arms on which the slats are pivotally 35 mounted, and a dash-pot connected with said arms to control the movement of the slats.

JOB HUTCHINSON.
